UNITED STATES PATENT OFFICE.

MOSES H. NICHOLS, OF HANCOCK, NEW YORK.

IMPROVED SHIPPING-CASE.

Specification forming part of Letters Patent No. 78,316, dated May 26, 1868.

To all whom it may concern:

Be it known that I, MOSES H. NICHOLS, of Hancock, in the county of Delaware and State of New York, have invented a new and Improved Air-Chambered Shipping-Case; and I do hereby declare that the following is a full, clear, and exact description thereof, which will enable others skilled in the art to make and use the same, reference being had to the accompanying drawings, forming part of this specification.

Figure 1 is a vertical diagonal section of my improved shipping-case, taken through the line xx , Fig. 2. Fig. 2 is a top view of the same, part being broken away to show the construction.

Similar letters of reference indicate corresponding parts.

My invention has for its object to furnish an improved shipping-case, designed especially for shipping butter and honey, but which may be used with equal advantage for other similar articles; and it consists in constructing the case air-tight, and with an air-chamber around the glass jar which contains the butter or honey to be shipped, and in the peculiar construction of the case by which this is effected.

A is the outer case, which is made rectangular in form, and of a size depending upon the size of the jar to be shipped in it. The joints of the case A should be packed or otherwise made perfectly air-tight. B are slides working in grooves in the sides of the case A, cutting off triangular spaces in the corners of said case, and reducing its interior to an octagonal form. C are cushions, made of rubber or other material possessing the requisite elasticity, attached to the slides B, so as to press against the sides of the jar placed within the case. The cushions C need not be continuous, but should either be continuous or sufficient in number to fully and sufficiently support the sides of the jar, and should be extended upon or attached to the bottom of the case A, so that the said jar may have an elastic support to rest upon.

D is the jar into which the butter has been packed, or within which the honey has been formed by the bees. The jar D is covered with

an air-tight cover, E, and the air that may be within the jar is then exhausted through the hole in said cover, which hole is then sealed up.

F is an octagonal cover fitting into the interior of the case, and having a rubber or other elastic cushion, C, attached to its lower side, which presses upon the cover E of the jar D. The upper side of the cover F is corrugated or grooved transversely, as shown in Fig. 1, so that the air may pass freely between it and the cover G of the outer case, A. The edges of the cover G enter and slide in grooves in the upper part of the said case A, and the various parts are so constructed and arranged that the cover G when slid into its place may press the octagonal cover F and its cushion down closely upon the cover E of the jar D. The outer case, A, may then be made entirely air-tight by covering the joint or joints of the cover E with gummed cloth or some similar material. By this construction the jar D that contains the material to be shipped will be surrounded with an air-chamber, the air within which, when the outer case, A, is closed, will remain unchanged, and being a non-conductor will prevent the contents of the jar from being effected by heat during its transportation to market.

It should be observed that the cases and jars are designed to be returned to the producer, so that his only expense will be procuring his first supply. The cases A, when shipped, are designed to be packed in cases or crates of such a size as to contain nine, twelve, or any other number of said cases A, according to their size and the weight of the material packed in them.

I claim as new and desire to secure by Letters Patent—

The combination of the slides B, octagonal cover F, and elastic cushions C with each other and with the case A and jar D, substantially as herein shown and described, and for the purpose set forth.

MOSES HIGBY NICHOLS.
